UNITED STATES PATENT OFFICE.

FRANK BUCHANAN, OF SYRACUSE, NEW YORK.

HEADLIGHT.

1,150,170.

Specification of Letters Patent. Patented Aug. 17, 1915.

Application filed October 28, 1911. Serial No. 657,363.

To all whom it may concern:

Be it known that I, FRANK BUCHANAN, a citizen of the United States, and a resident of Syracuse, in the county of Onondaga and State of New York, have invented a certain new and useful Headlight, of which the following is a specification.

This invention relates to head lights having incandescent electric lamps and it pertains particularly to means for adjusting the lamp axially of the light focusing means or reflector thereof, and the invention consists in the combinations and constructions hereinafter set forth and claimed.

15. In describing this invention reference is had to the accompanying drawings in which like characters designate corresponding parts in all the views.

Figure 1 is a front elevation of one form 20 of head light embodying my invention, the door of the case being open, and the lamp being removed from the socket. Fig. 2 is a sectional view, partly in elevation, on the plane of line "A—A," Fig. 1, the door being 25 shown as closed and the lamp being illustrated as inserted into its socket. Fig. 3 is an enlarged sectional view of the support for the lamp socket and contiguous parts. Fig. 4 is a sectional view on the plane of 30 line "B—B," Fig. 3, the wall of the case being omitted.

This head light comprises, generally, a case, a light focusing means or reflector in the case, an incandescent electric lamp within the reflector, a socket for the lamp, and means for supporting and adjusting the socket comprising a movable carriage, a stationary frame for supporting the carriage, and members associated with the frame for 40 moving the carriage and adjusting the lamp axially of the reflector. The members for moving the carriage and thereby adjusting the lamp axially of the reflector, are preferably arranged eccentric to the axis of the reflector and lamp socket and extend parallel thereto, and an operating part is arranged concentric with such axis and connected to said members.

45 1 is the case which is here shown as cylindrical in general outline and as having a hinged door 2 at its front end and a rear wall 3 opposed to such hinged door.

4 is the reflector located in the case 1 and having its front end secured to, and supported by, the front end of the case, and its rear end provided with an axial opening.

5 is the incandescent electric lamp adjustable lengthwise of the axis of the reflector 4; and 6 is the socket or support for the lamp, said socket being here shown as arranged coaxially with the reflector 4 so that the lamp 5 is held in horizontal position at the axis of the reflector 4.

7 is the carriage for the socket 6, said carriage being arranged at the rear of the reflector 4 and having a substantially central opening 8 by means of which the socket 6 may be secured thereto by any suitable fastening means. The plurality of members for moving the carriage comprise preferably three screws 9 spaced equidistant apart and arranged eccentric to, and parallel to, the axis of the reflector 4. Said screws are supported and held from endwise movement in any suitable manner and extend through threaded eyes or openings 10 in the socket carriage 7. As here illustrated the screws 9 are formed with axles 11 at their ends which are journaled in openings in suitable supporting elements as rear and front plates 12 and 13, which are arranged at the rear of the reflector 4 and, with connecting tie rods 14 constitute the stationary frame for supporting the carriage 7, the rear plate 12 being at the rear of the carriage 7 and engaging and being secured to the rear wall 3, and the front plate 13 being annular in form and supported in front of said carriage by the rods 14 projecting from the element 12 and said plate 13 being provided with a central opening or passage coaxial with the opening in the rear end of the reflector. Said rods extend through openings in the carriage 7 and have reduced threaded ends 15 extending through openings in the plate 13 and receiving suitable nuts 16 which turn against the outer face of said plate 13. The rods 14 are also formed with threaded reduced ends 17 which extend through openings in the plate 12 and 100 through the rear wall 3 of the case, and nuts 18 turn on such projecting ends against the wall 3 for securing the plate 12 and parts carried thereby in position. The plates 12 and 13, rods 14, screws 9 and carriage 7 constitute supporting and adjusting means for the lamp socket 6, and said means are supported independently of the reflector in order that said reflector may be free from all strains incidental to the support and adjustment of the lamp. The screws 9 are turned in order to move the carriage 7 and

105

110

the socket 6 carried thereby axially of the reflector 4, by a gear 19 mounted coaxially with the socket 6 and reflector 4 in rear of the reflector and engaged with pinions 20 mounted on and preferably formed integral with the screws 9. The gear 19 is provided on a revoluble stud or operating member 21 extending through the plate 12 and the rear wall 3 of the case coaxial with the reflector 4, and said gear is operated by means of a hand engaging part 22 mounted on the threaded outer end of the stud 21. Obviously by turning the part 22 the motion thereof will be transmitted by the gear 19, pinions 20 and screws 9 to the carriage 7.

15 The electrical connections for the terminals of the lamp socket may be made in any suitable manner and as such connections form no part of this invention, description thereof is unnecessary.

20 Owing to the arrangement of the means for adjusting the lamp 5 axially of the reflector 4, no holding means is required to hold the lamp in its adjusted position, and 25 owing to the use of a plurality of screws 9, binding of the carriage is prevented.

What I claim is:

30 1. In a head light, a case, light focusing means supported by the case, an electric lamp located at the axis of said means, a socket for the lamp, a carriage for the socket, a stationary frame for supporting the carriage, said frame being mounted on the case independently of the light focusing means, and means associated with the frame and 35 connected to the carriage for adjusting the carriage and the lamp lengthwise of said axis, substantially as and for the purpose described.

40 2. In a head light, a case, light focusing means supported by the case, an electric lamp located at the axis of said means, a socket for the lamp, a carriage for the socket, a stationary frame for supporting the carriage, said frame being located at the rear of 45 the light-focusing means and mounted on the case independently of said light focusing means, and means associated with the frame and connected to the carriage for adjusting the carriage and the lamp lengthwise of 50 said axis, substantially as and for the purpose specified.

55 3. In a head light, a case, light focusing means supported by the front end of the case, an electric lamp located at the axis of said means, a socket for the lamp, a carriage for the socket, a stationary frame for supporting the carriage, said frame being mounted on the rear wall of the case, and 60 means associated with the frame and connected to the carriage for adjusting the carriage and the lamp lengthwise of said axis, substantially as and for the purpose set forth.

65 4. In a head light, a case, light focusing

means supported by the case, an electric lamp located at the axis of said means, a socket for the lamp, a carriage for the socket, a stationary frame for supporting the carriage, said frame being mounted on the case independently of the light focusing means, means associated with the frame and connected to the carriage for adjusting the carriage and the lamp lengthwise of said axis, and a movable operating member extending through the case for actuating the last-mentioned means, substantially as and for the purpose described.

5. In a head light, a case, light focusing means supported by the front end of the case, an electric lamp located at the axis of said means, a socket for the lamp, a carriage for the socket, a stationary frame for supporting the carriage, said frame being mounted on the rear wall of the case, means associated with the frame and connected to the carriage for adjusting the carriage and the lamp lengthwise of said axis, a revoluble operating member concentric with the axis of the lamp and extending through said rear wall of the case for actuating the last-mentioned means, and power transmitting means between the concentric operating member and the carriage, the power transmitting means being connected to the carriage on opposite sides thereof, substantially as and for the purpose specified.

6. In a headlight, light focusing means, an incandescent electric lamp located at the axis of said means, a socket for the lamp, a carriage for the socket, a stationary frame for supporting the socket located in the rear of the light focusing means and having means associated therewith for coacting with the carriage at a plurality of points and operable to move the carriage to carry the lamp lengthwise of said axis, said means comprising rotatable screws arranged to engage threaded eyes provided on the carriage and an actuator common to said screws, substantially as and for the purpose set forth.

7. In a head light, a case, light focusing means supported by the case, an electric lamp located at the axis of said means, a socket for the lamp, a carriage at the rear of the light focusing means for supporting the socket, means for supporting the carriage independently of the light focusing means, and means at the rear of the light focusing means for moving the carriage and thereby adjusting the lamp axially of the light focusing means, said means comprising a plurality of members coacting with the carriage and arranged eccentric and parallel to the axis of the light focusing means, and an operating member common to all of said plurality of members, substantially as and for the purpose set forth.

8. In a head light, a case, light focusing means supported by the case, an electric

lamp located at the axis of said means, a socket for the lamp, a carriage for the socket, a stationary frame for supporting the carriage, said frame being mounted on the case independently of the light focusing means, and comprising a front element having an opening coaxial with the light focusing means, and means associated with the frame and connected to the carriage for adjusting the carriage and moving the lamp through the opening lengthwise of said axis, substantially as and for the purpose described.

9. In a head light, a case, light focusing means supported by the case and formed with an axial opening, an electric lamp located at the axis of said means, a socket for the lamp, a carriage for the socket, a stationary frame for supporting the carriage, said frame being mounted on the case and comprising a front element supported by the case arranged at the rear of the light focusing means and having an opening coaxial with the first-mentioned opening, and means associated with the frame and connected to the carriage for adjusting the carriage and moving the lamp through the openings lengthwise of said axis, substantially as and for the purpose specified.

10. In a head light, a case, light focusing means supported by the case, an electric lamp located at the axis of said means, a socket for the lamp, a carriage for the socket, a stationary frame for supporting the carriage, said frame being mounted on the case independently of the light focusing means, and comprising front and rear elements, the front element being formed with an opening coaxial with the light focusing means, screws journaled at their opposite ends in the front and rear elements and engaging threaded eyes provided on the carriage, and an operating member for actuating the screws, substantially as and for the purpose set forth.

11. In a headlight, a case, light focusing means supported by the case, a lamp arranged at the axis of said means, a socket for the lamp, a carriage for the socket, a stationary frame located in the rear of the lamp and comprising front and rear elements, and rods connecting said elements, the front element being formed with an opening through which the socket projects, screws journaled at their opposite ends in said elements and engaging threaded eyes provided on the carriage, the carriage being arranged to move between said elements, and an operating member common to said screws, substantially as and for the purpose described.

12. In a head light, a case, light focusing means supported by the case, an electric lamp located at the axis of said means, a socket for the lamp, a carriage for the socket, a stationary frame for supporting the car-

riage, said frame being mounted on the case independently of the light focusing means and comprising front and rear elements, the front element being arranged at the rear of the light focusing means and having an opening coaxial with the light focusing means, and rods connecting the front and rear elements, screws journaled at their opposite ends in said elements and engaging threaded eyes provided on the carriage, said carriage having openings for receiving the rods, and an operating member for actuating the screws, substantially as and for the purpose described.

13. In a head light, a case, light focusing means supported by the case, an electric lamp located at the axis of said means, a socket for the lamp, a carriage for the socket, a stationary frame for supporting the carriage, said frame being mounted on the case and comprising front and rear elements, the front element being provided with an opening coaxial with the light focusing means, and the rear element being mounted on the rear wall of the case, screws journaled at their opposite ends in the front and rear elements and engaging threaded eyes provided on the carriage, and an operating member for actuating said screws, substantially as and for the purpose specified.

14. In a head light, a case, light focusing means supported by the case and formed with an axial opening, an electric lamp located at the axis of said means, a socket for the lamp, a carriage for the socket, a stationary frame for supporting the carriage, said frame being mounted on the case independently of the light focusing means and comprising front and rear elements, the front element being arranged at the rear of the light focusing means and being formed with an opening coaxial with the light focusing means, and the rear element being mounted on the rear wall of the case, and rods connecting the front and rear elements, screws journaled at their opposite ends in said elements and engaging threaded eyes provided on the carriage, said carriage having openings for receiving the rods, and an operating member for actuating said screws, substantially as and for the purpose set forth.

15. In a head light, a case, a reflector within the case, an incandescent electric lamp within the reflector, a socket for the lamp, and a support for the socket comprising opposing elements at the rear of the reflector, said elements being supported independently of the reflector, one of the elements having a central passage coaxial with the reflector, a carriage upon which the socket is mounted, and means carried by the opposing elements for moving the carriage relatively to said elements, substantially as and for the purpose described.

16. In a head light, a case, a reflector within the case, an incandescent electric lamp within the reflector, a socket for the lamp, and a support for the socket comprising opposing elements at the rear of the reflector, rods connecting the elements, one of the elements engaging a wall of the case and being secured thereto, and the other of said elements being supported by the rods and having a central passage coaxial with the reflector, a carriage upon which the socket is mounted, and means carried by the opposing elements for moving the carriage relatively to said elements, substantially as and for the purpose specified.
17. In a head light, a case, a reflector within the case, an incandescent electric lamp within the reflector, a socket for the lamp, a support for the socket comprising opposing elements at the rear of the reflector, rods connecting said elements, one of said elements engaging a wall of the case and being secured thereto and the other of said elements being supported by the rods and having a central passage, screws journaled at their opposite ends respectively in said elements, a carriage upon which the socket is mounted, the carriage having threaded openings through which the screws extend and the socket being movable with the carriage through the passage of said element, pinions associated respectively with the screws, a stud extending through the element engaging said wall of the case and through said wall, the stud being arranged coaxially with the reflector, a gear mounted on the stud and meshing with the pinions, and a hand engaging part mounted on the stud on the outside of said wall of the case,

substantially as and for the purpose set forth.

18. In a head light, a case, a reflector within the case, an incandescent electric lamp within the reflector, a socket for the lamp, a support for the socket comprising opposing elements at the rear of the reflector, rods connecting the elements, one of the elements engaging a wall of the case and being secured thereto, and the other of said elements being supported by the rods and having a central passage, screws journaled at their opposite ends, respectively, in said elements, and a carriage upon which the socket is mounted, the carriage having openings through which the rods extend, and threaded openings through which the screws extend; and the socket being movable with the carriage through the passage of said element, pinions associated respectively with the screws, a stud extending through the element engaging said wall of the case and through said wall, the stud being arranged coaxially with the reflector, a gear movable with the stud and meshing with the pinions, and a hand-engaging member provided on the stud at the outside of said wall of the case, substantially as and for the purpose set forth.

In testimony whereof, I have hereunto signed my name in the presence of two attesting witnesses, at Syracuse, in the county of Onondaga, in the State of New York, this 26th day of Oct., 1911.

FRANK BUCHANAN.
